(Cl. D58—4)

To all whom it may concern:

Be it known that we, Earl F. Smith and Guy Kenneth Wilson, citizens of the United States and residents of Muncie, in the county of Delaware and State of Indiana, have invented a new, original, and ornamental Design for a Basket or Similar Article, of which the following is a specification, reference being had to the accompanying drawing, forming a part hereof.

In the drawing, Figure 1 is a side view, and Figure 2 is a top plan view of a basket or similar article showing our new design.

We claim:

The ornamental design for a basket or similar article, as shown.

EARL F. SMITH.
GUY KENNETH WILSON.
